UNITED STATES PATENT OFFICE.

SIDNEY GEORGE GRANT, OF LEICESTER, ENGLAND, ASSIGNOR TO UNITED SHOE MACHINERY COMPANY, OF PATERSON, NEW JERSEY, A CORPORATION OF NEW JERSEY.

FOLDING-MACHINE.

1,116,415.

Specification of Letters Patent.

Patented Nov. 10, 1914.

Application filed February 7, 1911. Serial No. 607,157.

To all whom it may concern:

Be it known that I, SIDNEY G. GRANT, a subject of the King of England, residing at Leicester, Leicestershire, England, have invented certain Improvements in Folding-Machines, of which the following description, in connection with the accompanying drawings, is a specification, like reference characters on the drawings indicating like parts in the several figures.

This invention relates to folding machines and particularly to the type of folding machines which are illustrated in the United States patent to Quentin W. Booth *et. al.*, No. 695,438, dated March 18, 1902. It has been found that in machines of this type at present in use it is extremely difficult to operate upon work of a certain shape. When the edge of the work to be folded is approximately at right angles to the direction of movement of the reciprocating folding members no difficulty occurs but as it is frequently the case that there is a considerable curvature so that portions of the edges of the work lie at only a small inclination to the direction of movement of the folding members then the folded over portion of the material is apt to be stretched out at certain parts and to form bunches at others, thus giving to the folded edge a want of uniformity in thickness and an inelegant appearance. In certain cases the outline of the material lies in parts at such a small angle to the direction of movement of the folding members that it is practically impossible to use machines of this type to perform the folding operation. It would therefore be advantageous if the folding members could be so formed and guided as to approach the edge of the material approximately perpendicularly, and an object of the present invention is so to form and guide those edges of the members which are farthest from the desired condition as to cause them to approximate more nearly to it.

To this end the present invention contemplates the provision of means for folding the marginal portion of leather or other sheet material, having two shaped folding members that are adapted to approach and overlap one another at their working edges, one or each of the said members having a section or sections so mounted and actuated

as to move in a direction at an angle to the direction of approach of the members. 5 Preferably the said sections may be pivoted each to its respective member and may be actuated in its motion relatively to the said member by a cam, but it is within the scope of the invention to mount the sections in any 6 other manner which will give the required result.

In the accompanying drawings, Figure 1 is a plan showing a portion of a folding machine of the type above referred to, wherein 65 a preferred embodiment of the invention is illustrated; Fig. 2 is an enlarged view showing the folding members and sections engaging the work to be folded; and Fig. 3 illustrates the same parts at the end of the folding operation. 70

The machine of the type shown in said patent comprises a table 1 on which the work to be folded is laid, a holder 2 to hold the work upon the table and to carry the 75 former plate 3, which plate determines the line of fold of the work 20. The former plate 3 is carried by the holder 2 by a plurality of headed screws passing loosely through appropriate slots in the former 80 plate and engaging tapped sockets in the holder in the usual manner, so that the former plate may be reciprocated relatively with the holder to the extent permitted by the length of the slots. The heads of the 85 screws contact with the work underneath the former plate and thereby hold the work 20 in position on the table while the former plate is moved forward to form the line of fold and afterward retracted to permit the 90 completion of the fold. The folder member 5 operates upon the work to form and to complete the fold as shown in said Booth patent.

In the embodiment of the invention about 95 to be described which is intended to act on material having a contour of edge that has considerable concavity the former plate has in its contour a recess of similar depth and shape while the folder has a corresponding 100 convexity. When the folder 5 is arranged for operation upon material having such a recess, by having a portion or portions of its contour intermediate between its ends approximately parallel to or at a comparatively small angle to the direction of move-

ment of the folding members, the said folder 5 has recesses 6 formed in said portions. In each recess is pivoted a section or auxiliary folder 8 which when forced back into its innermost position in the said recess will, with its edge and the edges of its carrying member 5, approximately complete the contour required to be formed along the edge of the material. When, however, a section is swung about its pivot 9 into its outermost or fold-pressing position its outer edge will be moved in a direction more nearly perpendicular to the edge of the material it is acting on than it would be by the movement merely of its carrying member.

Each section 8 has a cam slot 10 cut in it preferably near that end farthest from the end at which it is pivoted. Entering this cam slot is a pin 12 fixed to some relatively stationary part of the machine. The arrangement of the section, its pivot, cam slot, and pin, is such that when the folding members are in their retracted positions each section 8 will be in its innermost position in the recess 6. In the operation of the machine, as the members move forward to fold the edge of the material inwardly preparatory to pressing the fold the section is moved by the cam slot and pin about its pivot toward its outermost position, and will arrive at the said outermost position when the members have finished their folding action. Thus the resultant motion of the section 8 obtained by compounding the motion of the folder 5 as a whole with the motion which the section has relatively to the folder is more nearly perpendicular to the edge of the material being folded than it would have been had the section been absent. In this manner the fold produced is more even both as regards thickness and appearance than the fold produced by the machine of said patent, and moreover the material is not damaged or torn by the dragging of the edge as would formerly have been the case. When the folding members are retracted again the cam slot and pin will return the section to its first position ready to commence a new folding operation. It will be obvious that it is advantageous to provide one of these sections at each portion of the folder that approaches nearly to parallelism with the direction of movement of the folder and it is contemplated that this will be done. Although some advantage would be gained by providing only the folder with such sections it is preferable that the second of the folding members, namely, the former plate, also be provided with corresponding sections at those portions of its edge corresponding to the portions of the folder which are so provided. These sections, however, being in the side of the former plate instead of in the side of the folder, will commence the folding operation in their outermost po-

sition and finish in their innermost position but the resultant motion will as before be more nearly perpendicular to the direction of movement of the members.

In the present construction the former plate 2 has formed in it two recesses 7 in each of which a section 4 is pivoted at 14. Each section 4 has a cam slot 15 and a pin 16 that is fixed to the holder 2 and that as it remains stationary while the former plate moves forward to withdraw from the fold in the work gives the section the necessary movement about its pivot.

Having described my invention, what I claim as new and desire to secure by Letters Patent of the United States is:—

1. A machine of the class described having, in combination, a folder having a curved outline corresponding to that of the edge of the piece of material to be folded, said folder being provided with recesses located in its edge to the rear of its forward portion, auxiliary folders pivoted in said recesses and means responsive to the forward movement of said folder for swinging said auxiliary folders in opposite directions of angular movement about their respective pivots.

2. A machine of the class described having, in combination, a folder having a curved outline corresponding to that of the edge of the piece of material to be folded, said folder being provided with recesses located in its edge to the rear of its forward portion, auxiliary folders movably mounted in said recesses, and means responsive to the forward movement of said folder for effecting an outward movement of said auxiliary folders.

3. A machine of the class described having, in combination, a reciprocating folder, a reciprocating former over which said folder moves, said former having recesses in its edge, auxiliary formers located in said recesses and means responsive to bodily movement of said former for effecting a separating movement of said auxiliary formers.

4. A machine of the class described having, in combination, a reciprocating folder, a reciprocating former over which said folder moves, there being formed in said folder and former recesses located opposite to each other, an auxiliary folder located in a recess in the folder and an auxiliary former in an opposite recess in the former and means responsive to the movements of said folder and former in a given direction for moving said auxiliary folder and former in a different direction.

5. In a machine for folding the curved margin of a piece of material, a main folder having an outline which corresponds to the outline of said curved margin, said folder being provided with a recess, and an auxiliary folder located in said recess, said aux-

iliary folder being provided with a slot, a stationary pin located in said slot, a pivot connecting said folders, and means for moving said main folder in a given direction and thereby swinging said auxiliary folder in a different direction.

In testimony whereof I have signed my

name to this specification in the presence of two subscribing witnesses.

SIDNEY GEORGE GRANT.
